United States Patent Office.

ELIAS BROCK, OF ELLENVILLE, NEW YORK.

Letters Patent No. 66,124, dated June 25, 1867.

IMPROVED MACHINE FOR UNHAIRING HIDES.

The Schedule referred to in these Letters Patent and making part of the same.

TO ALL WHOM IT MAY CONCERN:

Be it known that I, ELIAS BROCK, of Ellenville, in the county of Ulster, and State of New York, have invented a new and improved Machine for Unhairing Hides; and I do hereby declare that the following is a full, clear, and exact description thereof, which will enable others skilled in the art to make and use the same, reference being had to the accompanying drawings, forming part of this specification, in which—

Figure 1 is a side view of my improved machine.

Figure 2 is an end view of the same.

Similar letters of reference indicate like parts.

My invention has for its object to furnish an improved machine for unhauling hides, and scrubbing, scouring, and washing leather conveniently, rapidly, and thoroughly. And it consists in the combination of a pair of feed-rollers with the knife-cylinder of an unhauling machine; in arranging the feed-rollers, knife-cylinder, and guide-roller with each other so that the hides or leather may be drawn over the knife-cylinder in a direction opposite to that in which the surface of the said cylinder is moving; in the combination of a roller with the frame of the apron, by which the hide or leather is held down upon the knife-cylinder; and in the arrangement of gearing, by means of which motion is communicated from the knife-cylinders to the feed-rollers, the whole being constructed and arranged as hereinafter more fully described.

A is the frame of the machine, near the middle part of which are formed the bearings for the journals of the knife-cylinder B. C are the knives or scrapers, which may be of any desired shape, and which are attached to the surface of the cylinder B in a line with its axis. D and E are the feed-rollers, which revolve in bearings in the frame A, and which are so arranged that the upper side of the upper feed-roller D may be considerably below the upper side of the knife-cylinder B, and so that the upper roller D may be a little nearer the said knife-cylinder B than the lower one E. The upper parts of the bearings of the upper roller D are movable, and are held down upon its journals by rubber springs or their equivalent. F is a guide-roller, pivoted to the forward part of the frame A, over which the hides or leather are spread, and from which they pass into the machine. G is the frame, to which the apron H is attached. The frame G is pivoted to the upper part of the front side of the frame A, and it is held down, pressing the hide or leather against the knife-cylinder B by taking hold of the hand-rail g¹. I is a roller, pivoted to the lower ends of the short arms g², projecting downward from the frame G, so that, when the said frame G is in the position shown in fig. 2, the hide or leather may pass through the machine without touching the roller I; but when the frame G is raised into the position shown in fig. 1, the hide or leather will be lifted away from the knife-cylinder B. Motion is communicated to the machine by applying power to the knife-cylinder B, by means of a crank or pulley J, attached to one of its journals. To the other journal of said knife-cylinder is attached a small gear-wheel, K, the teeth of which mesh into the teeth of the large gear-wheel L, pivoted to the side of the frame A, and which has a pulley, M, formed upon or securely attached to it. N is a band, which passes around the pulley M and around the pulley O, attached to the journal of one of the feed-rollers D E, which said journal has also a gear-wheel, P, attached to it, the teeth of which mesh into the teeth of the gear-wheel R attached to the journal of the other feed-roller. In using the machine, the pack is passed into it, tied together over the guide-roller F; thence it passes over the roller I, over the knife-cylinder B, and over and around the upper feed-roller D, passing out at the bottom of said machine, the feed-rollers D E drawing the hides over the knife-cylinder B in a direction opposite to that in which the surface of said knife-cylinder is moving. The hides, while passing through the machine, are held down by the apron H and frame G. The apron H may be made of canvas, rubber, leather, or any other suitable material, and should be removably attached to the frame G.

What I claim as new, and desire to secure by Letters Patent, is—

1. The combination of the pair of feed-rollers D E with the knife-cylinder B of an unhauling machine, substantially as herein shown and described, and for the purpose set forth.
2. Arranging the guide-roller F, knife-cylinder B, and feed-rollers D E, with each other and with the frame A of the machine, substantially in the manner herein shown and described, so that the hides or leather shall be drawn over the knife-cylinder B in a direction opposite to that in which the surface of the said knife-cylinder is moving.
3. The combination of the roller I with the frame G, to which the apron H is attached, substantially as herein shown and described, and for the purpose set forth.
4. Arranging the gearing K L M N O P R substantially in the manner herein shown and described, for the purpose of communicating motion from the knife-cylinder B to the feed-rollers D E.

ELIAS BROCK.
